(57) **CLAIM**

The ornamental design for a cap for a medical vial, as shown and described.

DESCRIPTION

FIG. 1 is a top perspective view of a cap for a medical vial of my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a cross-sectional view thereof; and,

FIG. 10 is a top perspective view thereof with the cap attached to a medical vial.

The broken lines depict portions of the cap that form no part of the claimed design. The broken lines showing the medical vial illustrate environmental structure which form no part of the claimed design.

1 Claim, 5 Drawing Sheets
